WASHING MACHINE DRIVE

Filed Dec. 12, 1928

UNITED STATES PATENT OFFICE

THOMAS S. WATSON, OF MILWAUKEE, WISCONSIN

WASHING MACHINE DRIVE

Application filed December 12, 1928. Serial No. 325,572.

The invention relates to washing machine drives.

Washing machines, as commonly constructed for use in laundries, are of a type including a stationary horizontally-disposed cylindrical casing having mounted therein a relatively long rotatable washing drum or cylinder, which is periodically reversed in its direction of rotation. Conditions require that the drum or cylinder be driven simultaneously at opposite ends and this has heretofore been accomplished by securing large gear wheels to the opposite ends of the drum or cylinder and meshing these gear wheels with pinions carried on a counter-shaft, which is driven through a gearing connection, usually including a second counter-shaft, by an electric motor or other source of power. Reversing has been accomplished either by the use of gearing mechanism, or by reversing the motor.

In practice, the washing machine drive heretofore provided has been found to be expensive in construction as well as noisy in operation, and it was difficult to effect and maintain a proper adjustment of the gearing to equalize the transmission of power to opposite ends of the reversible washing drum.

In order to obviate these disadvantages, it is an object of the present invention to provide a washing machine drive of simple, inexpensive and efficient construction embodying belting connections, the drive being quiet in operation and capable of simple adjustment to equalize driving torque at opposite ends of the drum.

A more specific object is to drive the rotatable drum at each end by means of multiple-grooved sheaves which have a multiple-V-belt driving connection with other sheaves carried on a suitably-driven counter-shaft, means being provided for independently adjusting opposite end portions of the counter-shaft with respect to the axis of the washing drum to equalize the transmission of power to opposite ends of the drum.

The invention further consists in the several features hereinafter set forth and more particularly defined by the annexed claims.

50 In the accompanying drawing, Fig. 1 is an

end elevation of a washing machine embodying the drive of the invention, parts being broken away and parts being shown in section;

Fig. 2 is a front elevation of the washing machine, parts of the driving belts being broken away and parts being shown in section, and

Fig. 3 is a detail sectional elevation taken on the line 3—3 of Fig. 2 showing the manner of adjusting one of the counter-shaft bearings.

In the drawing, the numeral 10 designates a stationary horizontally-extending cylindrical casing which, in practice, may be of considerable length. The casing 10 is supported at its ends on end frames 11 and at intermediate portions on suitable saddle frames 12, all as usual. A washing drum or cylinder 13 is disposed within the casing 10 and carries the usual shafts 14 at its ends which are journaled in the end frames 11.

In the usual type of washing machine heretofore constructed, large gear wheels were carried on the shafts 14 for driving the drum 13. In the present instance, however, gearing connections are not employed and use is made of a type of drive described in United States Letters Patent No. 1,662,511, issued March 13, 1928. The driving connection therein described consists essentially of a pair of multiple-grooved sheaves rotatable on parallel axes and connected by a plurality of independent elastic V-belts, which automatically establish equal driving ratios for all the belts during the rotation of the sheaves. The advantages of this type of driving connection are effectiveness in driving between "short centers", efficient transmission of power using relatively narrow sheaves, and quiet operation.

In carrying out the invention, a large diameter multiple-grooved sheave 15 is secured to each drum shaft 14, and these sheaves are connected by a number of elastic V-belts 16 with a pair of much smaller multiple-grooved sheaves 17 secured to opposite end portions of a counter-shaft 18 disposed longitudinally above the casing 10. The counter-shaft is journaled near its ends

- in a pair of self-aligning bearings 19 of the ball-and-socket type, each bearing including a bearing block 20 adjustably secured to the upper end portions of the end frames 11.
- 5 Each end frame 11 has its upper portions provided with a guide groove 21 in which slidably fits a rib 22 on the bearing block 20. Slots 23 are formed in the end frame to receive therethrough bolts 24, by means of 10 which the bearing can be fixed in position. Each bearing is capable of independent adjustment toward or away from the axis of the washing drum, and this is accomplished by means of a jack bolt 25 having a head at 15 its lower end engageable with a lug 26 on the end frame, and having a nut 25' threaded thereon in engagement with the bearing block, the upper end of the jack bolt entering the bearing block for guidance therein. The 20 adjustment of the nut 25' on the jack bolt 25 serves to accurately position the bearing when the bolts 24 are loosened, and these latter bolts are then tightened to maintain the adjustment of the bearing. In this manner, the V-belts 16 at opposite ends of the 25 drum may be given their proper tension to insure equal transmission of power to opposite ends of the drum. The use of the self-aligning bearings 19 permits independent 30 adjustment of the belt tension at opposite ends of the machine without causing binding of the counter-shaft, and a slight lack of parallelism between the counter-shaft and the axis of the washing drum is not objectionable, if this condition should result from 35 such adjustment. The driving connections at opposite ends of the drum are essentially identical with respect to the effective diameters of the sheaves 15 and 17 and the number 40 of belts connecting the sheaves.
- Another multiple-grooved sheave 27 is secured to the counter-shaft near one of its bearings 19 and is connected by a plurality of elastic V-belts 28 with a much smaller 45 multiple-grooved sheave 29 carried on the shaft of an electric motor 30, which is disposed rearwardly and downwardly from the counter-shaft. The motor 30 includes leg portions slidably mounted on a pair of upper 50 right supporting rods 31, which are fixedly secured to a cross member 32 connecting the end frames 11 of the machine. The tension on the V-belts 28 is properly adjusted by dropping the motor on its guide rods 31, to 55 which the motor is then fixedly secured by suitable clamping bolts 33. This adjustment of the tension on the V-belts 28 is made after the tension on the V-belts 16 is properly adjusted.
- 60 In operation, power is transmitted from the motor 30 to the counter-shaft 18, the driving connection between them also serving to effect a substantial speed reduction. Power is transmitted from the counter-shaft to opposite ends of the washing drum in substan-

tially equal proportions, thus distributing the load evenly between the two sets of driving belts 16 and minimizing torsional stresses in the washing drum. Since there is no metal-to-metal contact in the driving connections, the operation of the machine is unusually quiet and all shocks incident to varying load conditions are taken up by the elastic driving belts. 70

To reverse the machine, the direction of 75 rotation of the electric motor is periodically reversed by means of suitable switching mechanism well known in the art. In the present instance, the shock of the repeated reversals is taken up by the elastic driving 80 belts 16 and 28 to thereby prevent jarring of the mechanism. In its reversing operation, the washing drum may be brought to successive momentary stops by "plugging" the motor, and under these conditions the elastic 85 driving belts absorb the shocks which might otherwise injure the mechanism. A brake drum 34 mounted on the counter-shaft 18 serves as a means for locking the drum during the loading and unloading operations. 90

While the invention is more particularly adapted for use in cylinder washing machines, it will be obvious that it is also applicable to other types of machines where similar operating conditions are encountered. 95

What I claim as new and desire to secure by Letters Patent is:

1. In a washing machine, the combination of a frame structure including a pair of spaced end frames, a rotary washing drum 100 extending horizontally between said end frames and having shaft members at opposite ends journaled in said end frames, sheaves carried on said shaft members, a counter-shaft arranged substantially parallel to the axis of said drum, sheaves carried on said counter-shaft in alignment with the sheaves on the shaft members of the drum, belts connecting the sheaves of said drum and counter-shaft, means for driving 105 said counter-shaft, bearing blocks adjustably mounted on said end frames, self-aligning bearings carried on said bearing blocks for supporting said counter-shaft, and means for independently shifting said bearing blocks with respect to the axis of said drum 110 for adjusting the tension of said belts and equalizing the transmission of power to the opposite ends of said drum.

2. Power transmitting apparatus comprising, in combination, a rotary driven member, supporting means for said rotary member, pulleys mounted on the opposite end portions of said rotary member, a counter-shaft arranged substantially parallel to the 115 axis of said rotary member, pulleys carried on the opposite end portions of the counter-shaft in alignment with the pulleys on said rotary member, belts connecting said pulleys, means for driving said counter-shaft, 120

a pair of spaced self-aligning bearings for said countershaft adjacent the respective pulleys on said shaft, and supporting means on which said bearings are independently shiftably mounted for independently adjusting the tension of said belts to equalize the transmission of power to the opposite end portions of said rotary member.

3. Power transmitting apparatus comprising, in combination, a rotary driven member, supporting means for said rotary member, pulleys mounted on said rotary member at points spaced along the axis of said rotary member, a countershaft arranged substantially parallel to the axis of said rotary member, spaced pulleys on the countershaft in alignment with the spaced pulleys on said rotary member, belts connecting said pulleys, means for driving said countershaft, bearing means for supporting said countershaft at spaced points adjacent the pulleys on said countershaft, and means for independently displacing said countershaft bearing means for adjusting the tension of said belts and equalizing the transmission of power to the axially spaced points of said rotary member.

In testimony whereof, I affix my signature.
